UNITED STATES PATENT OFFICE.

ROBERT STEEL, OF PHILADELPHIA, PENNSYLVANIA, ASSIGNOR OF ONE-HALF TO THOMAS H. HAYES, OF SAME PLACE.

CAR-COUPING.

SPECIFICATION forming part of Letters Patent No. 371,861, dated October 18, 1887.

Application filed July 14, 1887. Serial No. 244,345. (No model.)

To all whom it may concern:

Be it known that I, ROBERT STEEL, a citizen of the United States, residing at Philadelphia, in the county of Philadelphia and State of Pennsylvania, have invented a new and useful Improvement in Car-Couplings, of which the following is a specification.

The object of my invention is to provide means for forming an effectual coupling, dispensing with the vertical loose pin now in use, and the danger of injury to those engaged in making up trains; and it consists of a rigid draw-head having an open loop or hook formed upon its end, and a pivoted link having its fulcrum below the center of gravity, for attachment to a similar hook upon the draw-head of the opposing car, the link not in use resting above the draw-head in slots of side plates. Each platform is provided with a draw-head, as will be more fully understood from the following description.

In the accompanying drawings, which make a part of this specification, Figure 1 is a plan view of a pair of connected draw-heads. Fig. 2 is a side elevation, the platforms A being cut through the broken line XX of Fig. 1. Fig. 3 is an end view. Fig. 4 is a side view of the draw-head B, the link C being removed. Fig. 5 is an end view of same.

Like letters of reference in all the figures indicate the same parts.

A are the extremities of platforms of a pair of cars; b, the bumpers framed therewith.

B is the draw-head, having the flanges or side plates, c, by means of which it is bolted to the end cross-timbers of the platform. It is formed

with the hook d upon its end, into which the end of the link C of the opposing draw-head engages by turning it over upon its pivotal point e in the orifice g of the head.

h are open slots in the plates c, that allow the link to rest in when not in use. The links, when not in use, are placed upright, inclining toward the body of the car at an angle of about forty-five degrees, in order that a sudden jolt or bump may not throw them downward previous to coupling. The draw-head is placed between two bumpers, of length sufficient to allow room upon their outer sides to allow of an operator standing in the space without endangering his safety.

In operation the links are placed in the position seen on the right in Fig. 2, and as the cars are brought closely together one link is thrown over upon its pivot until it assumes that seen on the left, falling into the inclined way, and as tension is exerted during the starting of the train, on and into the hook, securely coupling. Each platform is provided with a head and link, so that should a break of a link occur the opposite will be available.

I claim as my invention and desire to secure by Letters Patent—

In a car-coupling, the combination of the draw-head B, having side flanges, c, provided with slots h, hook d on its end, and pivoted link C, substantially in the manner herein shown and described.

ROBERT STEEL.
